CIRCULATOR FOR PICKLING BATHS

Albert Dietzel, Pittsburgh, Pa.

Application June 27, 1934, Serial No. 732,614

3 Claims. (Cl. 103—263)

The invention relates to pickling tanks, and particularly to a circulator for maintaining a pickling bath in proper condition for service.

A pickling bath is a body of acid in which metal articles are treated, and in practice it has been found desirable to heat and circulate the acid comprising the bath. Customarily, steam is employed to this end, and usually one or more steam pipes are caused to discharge below the surface of the bath. It has been realized that to achieve best results the steam pipes should each terminate in an injector or circulator, whereby the effect of the steam is enhanced, and uniform circulation of the bath is obtained. Manifestly, the steam pipes and injectors must be constructed of acid resisting material, and, while there are several well-known materials of this nature available, their use hitherto has been unsatisfactory, due either to the physical inadequacy of the material or to its high cost. No one has provided a durable injector structure which may be made of inexpensive acid-resisting material, such as lead, or acid-resisting ferrous alloys.

It is further remarkable that, when the steam is turned into a cold acid bath, the injectors used hitherto permit or cause a violent "hammering"—much like the well-known "water-hammer" so dangerous to pipe lines.

The object of my invention is to provide a durable injector structure which may be made of inexpensive acid-resisting metal, such as lead. It is further my aim to provide an injector of such structure, and to provide such an organization of the injector (or injectors) in a pickling tank, that the hammering alluded to is eliminated, or is reduced to a hammering of unobjectionable magnitude.

In the accompanying drawing Fig. I is a fragmentary view in vertical section of a pickling tank equipped with injectors in accordance with my invention; Fig. II is a view in side elevation, and Fig. III is a view in front elevation, of a circulator or injector embodying the invention; and Fig. IV is a sectional view of the injector, taken on the plane IV—IV of Fig. III.

Referring to the drawing, the numeral 1 indicates a pickling bath, and 2 a tank of typical structure—lined with sheet lead 3—in which the bath is contained. At desired points in the bath 1 injectors 4 are organized; in accordance with the invention the injectors 4 are of such structure that they rest securely upon the floor of the tank, and steam supply pipes 5 extend adjacent the side walls of the tank, downward into the bath, and severally terminate in the injectors.

Each injector comprises a hollow T-shaped body; the hollow cross-branch 6 of the T is open at its opposite ends, and communicates with a passage 7, extending through the central stem 8 of the T. The steam employed in the operation of the injector is directed into the passage 7 of the central stem of the T. In service (in accordance with well-known laws of fluid flow) the steam in flowing through passage 7, draws acid inward in opposite directions through the open ends of the cross-branch 6, and discharges it through the passage 7. The acid drawn into the cross-branch is relatively cool, and upon its discharge from the passage 7 is relatively hot, the steam condensing and giving up its latent heat of vaporization in the passage 7.

It will be understood that the T-shaped body of my injector may be readily cast of lead, and an opening may be cored out in the wall of the cross-branch 6, for the introduction of the steam jet. Advantageously, the steam supply pipe is formed of lead; its lower end is curved, as shown, and projected through the opening in the wall of the cross-branch 6; union of the pipe 5 and cross-branch 6 is effected by welding or "lead-burning"; the terminal of the pipe 5 provides a discharge orifice 5a directed toward or into the passage 7, and a clearance 9 is provided between the periphery of the orifice 5a and the wall of passage 7, to admit of the flow of acid from the body portion 6 and into passage 7. The wall of the stem portion 8 is relatively heavy, whereby the device is adapted long to withstand the erosive action of the steam and acid flowing through passage 7.

Advantageously, the whole device may be constructed of standard lead pipe, cut to length, appropriately fashioned, and united; in a typical case the cross-branch 6 is formed of an eight inch length of 5" O. D.—4" I. D. lead pipe; the central stem 8 is formed of a six inch length of 4" O. D.—2½" I. D. lead pipe; the supply line 5 comprises a suitable length of 2" O. D.—1" I. D. standard lead pipe; the wall of the pipe 6 is provided with an orifice to receive the supply line 5, and with an opposite orifice conforming to the passage 7 of the stem 8, and the three parts 5, 6 and 8 are integrated by "lead-burning."

It will be observed that in service the T-shaped body 6, 8 extends horizontally upon the floor of the tank. To the end that a firm seating of the device upon the floor may be obtained, the central-stem 8 is offset vertically from the cross-branch, so that the bottom faces of the stem and cross-branch extend in common plane (Fig. IV).

Thus, the central-stem of the T provides in the direction of its extent support for the injector, while the opposite arms of the cross-branch of the T provide lateral support for the injector at 5 points lying outward from the opposite sides of said central-stem. A vertical member 10 reinforces the integration of the members 5 and 6; the member 10 includes a lower edge 10a which extends in said common plane, and provides still 10 further foundation for the firm seating of the device upon the floor of the tank.

In providing a body of hollow T-shape, the inlets or acid at the opposite ends of the cross-branch 6 are approximately double the area of 15 the outlet of passage 7; a relatively large effective area of contact with the bottom of the tank is provided; and a relatively great mass of material is concentrated at the outlet end of steam pipe 5. With apparatus of this sort I obtain in 20 largest measure the advantages alluded to.

I claim as my invention:

1. A steam injector for pickling baths and the like, comprising a heavy walled, hollow, T-shaped body of lead adapted to rest in substantially horizontal position upon the floor of a pickling tank, 25 the bore of the cross-branch of the T being open at its opposite ends, and the bore of the central-stem of the T communicating with the bore of said cross-branch, and a steam inlet extending angularly from the vertical adjacent the wall of said cross-branch and being directed through said wall transversely of said cross-branch and toward the bore of said central-stem, the aforesaid structure providing an acid resisting injector capable 30 of withstanding mechanical shock without fracture, and adapted to minimize "hammering," while being capable in service of withstanding the erosive action of steam fed thereto by said inlet.

2. A steam injector for pickling baths and the like, comprising a heavy walled, hollow, lead body of T-shape, the bore of the cross-branch of the T being open at its opposite ends, and the bore of the central-stem of the T communicating with the bore of the cross-branch, and a steam inlet directed through the wall of said cross-branch and toward the bore of said central-stem, said structure providing a lead injector capable of 10 withstanding in service the erosive action of hot steam, said body being adapted to extend horizontally with the central-stem of the T providing support in the direction of its extent, and said cross-branch providing lateral support at regions 15 lying outward substantial intervals from the opposite sides of said central-stem.

3. A steam injector for pickling baths and the like, comprising a heavy walled, hollow, T-shaped body of lead adapted to rest in substantially horizontal position upon the floor of a pickling tank, 20 the bore of the cross-branch of the T being open at its opposite ends, and the bore of the central-stem of the T communicating with the bore of said cross-branch, and a steam inlet extending angularly from the vertical adjacent the wall 25 of said cross-branch and being directed through said wall transversely of said cross-branch and toward the bore of said central-stem, the aforesaid structure providing an acid resisting injector capable of withstanding mechanical shock 30 without fracture, and adapted to minimize "hammering," while being capable in service of withstanding the erosive action of steam fed thereto by said inlet, the central-stem of the T being of less cross-section than the cross-branch 35 and being offset from the axis of said cross-branch, substantially as described.

ALBERT DIETZEL.
